Fig. 1.

Fig. 2.

Fig. 3.

Figure 1 is a perspective view of a construction toy element, showing our new design;

Figure 2 is a plan view thereof; and

Figure 3 is a view in side elevation.

The characteristic feature of our design being in a circular disc having octagonally disposed radial slots opening into the periphery of the disc in combination with T-shaped slots having head portions disposed symmetrically to form a square about a central aperture of the disc and having leg portions in linear alignment with alternate radial slots of the disc.

We claim:

The ornamental design for a construction toy element, as shown and described.
